STIRRER FOR ROTARY DIGESTER

Ward D. Harrison, Phillipsburg, N. J., assignor, by mesne assignments, to Riegel Paper Corporation, New York, N. Y., a corporation of Delaware

Application May 12, 1954, Serial No. 429,283

3 Claims. (Cl. 92—18)

This invention relates to the production of pulp for paper making, and more particularly to the cooking of a mass of raw material with a suitable liquor to form such pulp.

In making pulp, the raw material from which the fibers are to be obtained is mixed with a suitable liquor, the nature of which depends upon the raw material, and the mixture is heated for a predetermined period of time during which it is normally agitated to a certain extent to improve the chemical action of the liquor on the raw material. During cooking the lignins, dirt, etc., are removed from the raw material by the liquor and subsequent to cooking the liquor is withdrawn from the mixture and the pulp fibers delivered to a subsequent treating operation. I have found that this cooking operation, which is carried out in a receptacle known as a digester, can be substantially improved if the mixture of raw material and cooking liquor is handled in a manner not heretofore employed. Hence I have found that a more uniformly better cooked pulp with less shives, raw fibers and ligneous materials can be obtained, all other factors remaining the same, when the manner of handling the mixture of raw material and liquor proposed below is employed rather than that which has heretofore been employed. Or in the alternative, I have found that by handling the mixture of raw material and liquor in a digester in the manner I propose, a pulp of equal or perhaps slightly better quality can be obtained than has heretofore been possible while employing substantially less chemicals in the liquor, the pulp additionally being more uniformly cooked.

According to my invention, a mixture of the raw material from which the pulp is to be made and a suitable liquor therefor is placed in a digester and heated for cooking. Portions of the mixture of raw material and liquor are then repeatedly moved from the lower part of the mass thereof to an upper part of the mass with a substantial amount of the liquor of such portion being removed or withdrawn entirely from the mass and returned thereto by spilling it over a substantial area onto the top of the mass. In this manner the mixing of the raw material and liquor is greatly improved, with the raw material consequently being more uniformly treated by the liquor, and conversely with the liquor being employed more efficiently. Hence a considerable saving in the amount of chemicals that must be necessarily employed in the liquor to accomplish a predetermined degree of cooking is effected.

My invention also contemplates the provision of a novel apparatus by which the above method of treating a mixture of raw material and liquor may be carried out.

For a better understanding of my invention, reference may be made to the following more specific description thereof taken in connection with the accompanying drawing in which one form of apparatus according to my invention is illustrated and in which:

Fig. 1 is an elevation of said apparatus partly in section;

2

Fig. 2 is a plan view in section taken along line 2—2 of Fig. 1; and

Fig. 3 is a fragmentary elevation in section taken along line 3—3 of Fig. 1.

5 In the drawings there is illustrated a rotary digester 10 of the globe type having hollow trunnions 11 and 12 by which it is supported in fixed bearings 13 and 14. Through each hollow trunnion extends a steam pipe 15, the inner ends of which extend to diametrically opposed positions adjacent the inner face of the wall of the digester 10. The digester may be revolved by rotation of either of its trunnions by means not shown. Rotary steam joints permit the steam inlet pipes to rotate with the digester. An opening is provided in the wall of the digester 10 adapted to be sealed closed by a cover member 16. The raw material and liquor may be supplied to the digester and removed therefrom through this opening. During operation of the digester, of course, cover member 16 is tightly clamped in place to close the opening with a pressure tight seal.

Within the digester, and preferably opposite the filling opening thereof, a rake indicated generally at 17 is mounted. The rake comprises a plate 18 having an arcuate edge secured as by welding to the inner wall of 25 the digester, thus forming a baffle. A flange 19 extending substantially at right angles to the plane of plate 18 is secured to the inner edge of the plate throughout the extent thereof. A plurality of fin plates 20 of varying sizes are secured on one side of plate 18 to the plate 30 and to the wall of the digester. These plates extend substantially at right angles to the plane of plate 18. A plurality of plates 21 of varying sizes are secured to the wall of the digester on the opposite side of plate 18. Each of plates 21 is additionally secured to a rod 22 which 35 is in turn secured as by welding to plate 18. Plates 21 and rods 22 extend a substantial distance beyond the inner edge of plate 18 and are adapted to act as spaced tooth members in a manner similar to the teeth of a conventional rake when the digester is rotated with a mass of pulp and liquor therein. Plates 21 also, as may be seen in the drawings, extend substantially at right angles to the plane of plate 18.

In operation, the digester 10 is filled about $\frac{3}{4}$ full with a mixture of raw material and liquor. The cover 45 16 is then securely closed and the digester rotated. Steam is forced into the digester through steam pipes 15. In the particular digester shown steam is admitted alternately through the two steam pipes when each is in the vicinity of the bottom of its path of travel, the steam being therefore projected upwardly through the mass of raw material and liquor. In order to obtain a predetermined temperature and pressure within the digester during operation, it has been found necessary, when the steam 50 pressure has risen to about half that desired, to relieve non-condensable gas by closing off the steam supply and blowing back or venting through the trunnion to atmosphere employing for this purpose one steam pipe 15 located during the period of this operation in the vapor area of the digester. Admission of steam is then resumed and continued until the proper temperature and pressure has been reached. From this time on, the steam is continually injected into the digester to maintain the desired temperature and pressure therein.

60 During rotation of the digester and cooking of the mass of raw material and liquor therein, the rake 17 effects thorough mixing of the liquor and raw material. The digester is rotated so that the rake will move in the direction indicated by the arrow in Fig. 3. As the rake moves from its lowermost position, as shown in Fig. 3, upwardly its plate 18 moves a portion of the mass of the mixture upwardly with it. As the rake approaches its

horizontal position, some of the mass of raw material and liquor starts to spill therefrom. However, part thereof is maintained on the plate by reason of flange 19 and carried further upwardly, and in fact above the level of the mass within the digester. A good portion of this part is liquor which is then spilled over flange 19 as the rake progresses upwardly above the top of the mass. The last of the liquor, and of course some raw material mixed therewith, spills over the flange 19 only after the rake has passed its uppermost position and has started to descend.

The manner in which the rake shown agitates and mixes the mass of raw material and liquor during rotation of the digester in the cooking thereof has, as previously indicated, resulted in a substantially more uniform cooking and has enabled a substantial saving in the amount of the chemical components of the liquor necessary. The following clearly illustrates this saving.

The above digester is presently being employed to cook rope. The digester is filled about $\frac{3}{4}$ full with a mixture of rope, water and caustic soda, the amount of each in the mixture being as follows: For each pound of rope there is employed $2\frac{1}{2}$ to $3\frac{1}{2}$ lbs. of water and .06 to .08 lb. of caustic soda. When necessary, emulsifying agents may be employed in appropriate amounts for degreasing, etc. Steam is injected until the pressure within the digester is from about 60 p. s. i. to about 100 p. s. i. The cooking operation is continued for about 9 hours, 2 to 3 hours of this time being required to get the digester up to the desired temperature and pressure.

It has been found that the pulp obtained by the above operation is of equal or better quality than that which has heretofore been obtainable only with the use of .10 pound caustic soda per pound of rope. It has also been found that the resulting pulp is somewhat freer of shives, raw fiber and ligneous material.

Rag has also been effectively cooked in the above apparatus with a substantial saving in the chemical content of the liquor and with increased uniformity of the resulting pulp. I also contemplate that many materials which it has heretofore not been possible to satisfactorily cook in a rotary digester may now be efficiently and economically treated therein. Hence it is believed that such materials as corrugated waste, raw wood waste and raw kraft cook waste may now be satisfactorily and economically treated.

Various changes and modifications in my method and

apparatus as specifically disclosed will of course occur to those skilled in the art, but it should be clearly understood that my invention contemplates such changes and modifications as are within the skill of the art without a departure from the scope thereof, and hence the invention should be limited only to the extent set forth in the appended claims.

I claim:

1. In a rotary digester for cooking a mixture of a raw material and a suitable liquor to form a pulp, a rake secured to the inner wall of the digester and extending therein in a direction parallel to the axis of rotation of the digester, said rake comprising a main plate disposed in a radial plane including the axis of rotation of the digester, a flange extending along the inner edge of the main plate substantially at a right angle to the plane of said main plate, and a plurality of fin plates secured to said main plate and lying in planes substantially at right angles to the planes of the main plate and flange.
2. A rotary digester as set forth in claim 1 in which some of the fin plates are on one side of the main plate and others are on the other side thereof, the fin plates on one side of said main plate extending inwardly of said inner edge of said main plate.
3. In a rotary digester for cooking a mixture of a raw material and a suitable liquor to form a pulp, a rake secured to the inner wall of the digester and extending therein in a direction parallel to the axis of rotation of the digester, said rake comprising a main plate disposed in a radial plane including the axis of rotation of the digester, a flange extending along the inner edge of the main plate substantially at right angles to the plane of said main plate and a plurality of spaced tooth members extending inwardly from said flange.
